Patented Oct. 17, 1922.

UNITED STATES PATENT OFFICE.

MAX M. GOLDMAN, OF SOMERVILLE, AND EDWIN R. THAYER, OF BRIGHTON,
MASSACHUSETTS.

EMPLOYMENT RATING SHEET.

Application filed May 12, 1919. Serial No. 296,380.

To all whom it may concern:

Be it known that we, MAX M. GOLDMAN, a citizen of the United States, and a resident of Somerville, county of Middlesex and 5 State of Massachusetts, and EDWIN R. THAYER, a citizen of the United States, and a resident of Brighton, county of Suffolk and State of Massachusetts, have invented 10 Employment Rating Sheets; and we do hereby declare the following to be a full, clear, and exact description of the invention, such as will enable others skilled in the art to which it appertains to make and use the 15 same.

This invention relates to rating sheets for servants or employees. It has been the custom, so far as we are aware, to hire employees on the basis of a mental opinion 20 formed during an interview. No two persons would form the same opinion in regard to the rating of a prospective employee, and in fact, the opinion of any one person would vary from day to day, even if the facts were 25 the same. It will thus be seen that there is a large personal factor in following the system heretofore used.

We have devised a system of rating employees, which is based upon a wide knowledge 30 of the various trades, and the value of the length of experience in such trades, and is, therefore, accurately indicative, in the great majority of cases. Our improved system is based on carefully devised numerical 35 ratings, and by using such system, an employee will get the same rating, regardless of the person making the same. The manner in which we accomplish this purpose will be explained in the following description, 40 reference being had to the drawings, in which the single figure is a rating sheet embodying the invention.

At the top of the rating sheet are blanks 45 for the designation of the trade, the insertion of the name of the employee or applicant and the date. In the drawing these have been given as "Machinist," "John Doe" and "Jan. 2, 1919", by way of example. At 50 the left of the drawing is a column containing the total length of experience in a trade, the numbers being given as years of service, though any other unit may be adopted, if desired.

During the early period of a tradesman's 55 employment he is young and of a receptive

mood. Consequently, his increase in knowledge and skill increases quite materially every year. However, after a certain time of employment the increase is of a less extent and this gradually diminishes until a maximum point is reached. It is, therefore, preferable to list each year (in the column for years of experience) for a number of years, and then to skip a year or two until eventually the numbers increase by fives. 65 This, however, is not essential, as far as this invention is concerned, but we have found it to be preferable.

Adjacent to the column containing the total years of service, we arrange one or 70 more columns containing the rating to be given a tradesman from his experience in particular branches of the trade in question. On the drawings we have shown three columns under "Nature of experience" and "Rating values", one containing the rating for a tradesman having all marine experience, a second one containing ratings for a tradesman having part marine and part general experience and a third for one having general experience only, the rating sheet being 75 made suitable for use in ship yards and other places where marine experience is of importance. In certain trades, such as with 80 molders, there need be only one rating column adjacent to the column of years of experience, and this would correspond to the column headed "All marine" on the drawing.

On the rating sheet are a plurality of subdivisions applicable to various trades, such as "Machinist," "Electrician," "Moulder," "Copper smith," "Plumber" and "Boiler maker." A greater or less number of trades, 90 of course, may be placed on the sheet. 95

Referring to the "Machinist" sub-division, it will be noted that there are two general branches containing particular kinds of work in which a machinist may have had practical experience, the first group relating 100 to shop experience and the second, ship experience, the sheet being purposely made up for marine use. In both of the shop and ship branches definite ratings have been assigned opposite each particular class of work 105 to indicate the value or rating of the employee who has had experience therein.

Referring to the "Electrician" division, it will be seen that there are two sub-divisions, one listing the branches of the outside work 110

and the other that of inside work. Each of the particular kind or branches of the work has a numerical rating to be assigned to the employee who has had experience therein.

5 The arrangement of the other trades, namely, molder, copper smith, plumber and boiler maker will be apparent from the drawing, as the particular branches of the work are plainly listed and the ratings to 10 be assigned for each are fully shown in the columns adjacent thereto. A description of these is, therefore, unnecessary.

At some portion of the sheet (on the drawing they are shown at the right) is a 15 numerical list extending from 1 to 100, with adjacent checking columns to permit the checking off of the sum total of an employee's ratings, and an additional column is provided to permit the classification of the 20 employee as a first, second or third class one. The rating in this respect may vary, but we have found it a practical and successful plan to rate all who have a total above 61 as first-class, those from 31 to 60, as second 25 class, and those from 10 to 30, as third class. Obviously, it would be permissible to omit the numbers in the total marking values and the rating equivalents, and merely provide blanks for the insertion of the total rating 30 and the class of the applicant, but it is more convenient to arrange it as we have shown it on the drawing.

Having described the general plan of the 35 rating sheet, we will now assume the case of an applicant for a position, with the resultant rating, as follows:

During the interview, one having charge 40 of the employment bureau, by questioning the applicant, John Doe, learns that he is a machinist. Consequently, the word "Machinist" is written down after the word "Trade" near the top of the rating sheet. Further questioning will be assumed as follows: Q. How long have you worked at the 45 trade? A. Ten years. (Check mark No. 1 on the drawing is placed opposite 10 in the length of experience); Q. Has your experience been all marine, marine in general, mixed, or general only? A. All marine. 50 (Check mark No. 2 is placed in the "All marine" column at the right-hand side of numeral 10, indicating the years of experience); Q. Are you a shop man or an outside man? A. Shop man. (Having learned 55 this branch of the trade that the applicant has followed, further questioning is limited to the sub-division of this branch). Q. Can you run an engine lathe? A. Yes. (Check mark No. 3 is placed down opposite "Engine 60 lathe"); Q. Vertical boring mill? A. No; Q. Horizontal boring mill? A. Yes; Q. Planer? A. Yes; Q. Shaper and drill? A. Yes; Q. Any type of grinder? A. No; Q. Ever do erecting work and bench work? 65 A. Yes; Q. Did you ever operate screw

machines? A. Yes, I am familiar with both tooling up and operating.

As fast as the questioner receives the answers, he cross-checks in the blank space opposite the rating of each special kind of work in which the applicant is experienced, making no checks opposite those in which the applicant is inexperienced. By referring to the drawings, it will be seen that the cross-check marks are entered up in accordance with the applicant's statements. The rating obtained by the applicant from his length of experience as a machinist gives him forty points, and the sum of his ratings given him from his particular knowledge of particular kinds of shop work amount to twenty-six points. The applicant's total or resultant rating is, therefore, the sum of forty and twenty-six which is sixty-six. At the right of the drawing a check mark is placed opposite numeral 66, to indicate the total rating of the applicant. This, however, could be written down by the interviewer in a single blank space provided for the purpose, as previously described. Since sixty-six points are above the required number sixty-one, the applicant is given a rating as a first-class machinist, as indicated by a cross-check in the upper part of the "Rating equivalents" column. By following out this plan of rating employees and applicants, it is possible to get a man's resultant rating within a minute or so after the interview commences and since the numerical ratings have been carefully worked out from long 100 experience with tradesmen, more accurate results are obtained than if the interviewer were of the highest skill in judging from his personal observation. Furthermore, any one unskilled in the art of hiring men, can 105 rate the applicant fully as well as a skilled person. Consistent results are, therefore, obtained, which are entirely just, both to the employer and the applicant.

We have assumed the case of an applicant 110 for a position and the rating of him by the employer, so as to determine the man's pay and classification. This obviously depends upon the answers given by the applicant, but in any system the rating of an applicant is 115 likewise dependent upon his statements.

The rating sheet is fully as useful for rating employees as in rating applicants, but in this use of the rating sheet the employee 120 would not be interviewed, as the foreman or other person in charge is capable of filling out the rating sheet from his own personal knowledge of the employee. The foreman, or other person filling out the sheet, will not, however, be required to use his individual 125 opinion of the man, but will place down the cross-marks opposite the ratings, just as in the case of the applicant previously described.

It will be apparent that our improved rat- 130

ing or classification sheets can be used in the various professions and occupations, and the invention is not to be limited to mechanical trades. The sheets are also capable of use 5 in industrial employment bureaus, in labor unions, in Federal departments and other offices. Our improvement will be found of particular value in settling and adjusting strikes and various labor disputes and disturbances.

The invention is not limited to the exact details described, as these are given by way of example. Obviously, modifications will be advisable in certain trades, but in general, the system of rating is the same.

Having described our invention, what we desire to claim is:

In servant rating sheets for a given occupation, a first column containing numbers

to denote the total years of experience of a servant in the trade, a parallel column containing numbers indicative of the value of each number of years experience given by the first column, a third column containing a list of different kinds of work to be done 25 in the said occupation, a fourth column paralleling the third column, containing numbers indicative of the value of experience in the different kinds of work and a fifth column containing numbers adapted to be 30 checked and which checked numbers represent the complete rating of the servant.

In witness whereof, we have hereunto signed our names this 16th day of April, 1919.

MAX M. GOLDMAN.
EDWIN R. THAYER.
